UNITED STATES PATENT OFFICE.

HENRI TEISSEIRE, OF PARIS, FRANCE.

HINGE FOR VEHICLE-BODIES.

1,378,149.

Specification of Letters Patent.

Patented May 17, 1921.

Application filed October 23, 1917. Serial No. 198,167.

To all whom it may concern:

Be it known that I, HENRI TEISSEIRE, a citizen of the Republic of France, residing in Paris, France, have invented certain new and useful Improvements in Hinges for Vehicle-Bodies, of which the following is a specification.

This invention has for its object an improved hinge for use on vehicles (particularly automobiles) which are convertible in a manner to be either open or closed, and in which the window frames in the top are independent of the carriage doors.

The improved hinge is attached to the upper part of the fixed portion or tonneau of the carriage and its axis or spindle is adapted to receive a connecting part of the removable top of the carriage in line with the extension of the pivot axis.

One form of the improved hinge is shown in the accompanying drawing, in which:—

Figure 1 is an elevation, partly in section, of the hinge.

Fig. 2 is a horizontal section on the line X X in Fig. 1.

Fig. 3 is a side elevation of a vehicle body, showing the application of the invention to the doors thereof.

In the illustrated embodiment of the invention, the hinges comprise tubular or pivotal portions or eyes, and leaves or fastening plates united thereto respectively. The inner pivotal member is a tubular spindle, being a hollow sleeve, its bore forming a socket *t* to receive the outwardly prolonged pindle *a*, on which is pivoted the window frame in the removable top.

In the construction shown, the tubular spindle or sleeve *b* is attached to the middle plate *h*, which connects the hinge with the body or door; and the tubular portions *x¹*, *x²*, are integral with plates *c*, *d*, respectively. The tubular sleeve *b* is reduced at its end portions *b¹*, *b²* to form journals which enter within the tubular portions *x¹*, *x²* forming thus a hollow pindle for the hinge.

In Fig. 1 the upper pindle *i* is shown as slightly raised out of its socket; but when in use it is pushed down within the socket *t* until its stop shoulder *a* abuts against the top of the hinge. The socket *t* is coaxial with the axis on which the hinge members turn.

It will be noted that the hinges are embedded in the thickness of the casing of the carriage body, this special arrangement be-

ing employed for the purpose of obviating the placing of the pindle *i* in a plane outside the body which would necessitate either the corresponding window frames having an analogous position, which would cause gaps allowing air to pass, or the use of special articulations.

The hinge being thus constructed, the pivotal axis of the window frame is exactly in the extension of the axis of the door hinge; it suffices to mount the window frame above the door by any suitable means, such as for instance by means of a catch or a screw rod, in order that the door and the window frame can open and close together by turning properly around the same axis and remaining consequently in the same vertical plane.

It is quite evident that the invention need not be limited to the above described construction, and that any suitable modification can be adopted in each particular case. For example, in order to effect the juncture of the two spindles, either one may be bored out to receive the other, it being within the invention to invert the construction with the same result as in the described construction.

Having thus described my invention and the best means I know for carrying the same into practical effect, what I claim is:—

1. A hinge for the door of a vehicle body having a removable top, comprising hinge eyes and lateral attaching plates, the hinge eyes formed as tubular sleeves, the inner one forming a coaxial socket adapted to receive the pindle of a hinge for a window of such detachable top.

2. A hinge comprising lateral attaching plates and tubular pivotal sleeves on such plates respectively, the inner pivotal member being tubular to form a coaxial socket for receiving a detachable pindle.

3. The combination with a vehicle body having a removable top, the body having a door and the top a hinged window sash above the door, of a hinge comprising tubular pivotal portions, the inner one forming a tubular spindle, and a prolonged pindle entering the hollow of such tubular spindle.

4. A door hinge for a vehicle body having a removable top, comprising tubular pivotal sleeves, one within the other, the inner one forming a socket adapted to receive the pindle of the hinge of a window sash in the removable top.

5. A hinge comprising an inner tubular sleeve having a middle attaching plate, the end portions of the sleeve beyond such plate being reduced to form journals, and outer sleeves turning on such journals and having attaching plates.

In witness whereof I have hereunto signed

my name in the presence of two subscribing witnesses.

HENRI TEISSEIRE.
